CLAIM

The ornamental design for a stator, as shown and described.

DESCRIPTION

FIG. 1 is a perspective view of a stator showing my new design;

FIG. 2 is a front elevation view thereof;

FIG. 3 is a back-side elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a detailed rear elevation view thereof;

FIG. 9 is a cross sectional view of line A—A of FIG. 2, thereof; and,

FIG. 10 is a cross sectional view of line B—B of FIG. 2, thereof.

The broken lines shown are for illustrative purposes only and form no part of the claimed design.
